UNITED STATES PATENT OFFICE.

JAMES L. WOOLDRIDGE, OF DECATUR, TEXAS.

MOTE-BOARD FOR COTTON-GINS.

1,308,651.

Specification of Letters Patent.

Patented July 1, 1919.

Application filed October 19, 1917. Serial No. 197,448.

To all whom it may concern:

Be it known that I, JAMES L. WOOLDRIDGE, a citizen of the United States, residing at Decatur, in the county of Wise and State of Texas, have invented certain new and useful Improvements in Mote-Boards for Cotton-Gins; and I do hereby declare the following to be a full, clear, and exact description of the invention, such as will enable others skilled in the art to which it appertains to make and use the same.

This invention relates to improvements in mote boards for cotton gins and the primary object of the invention is to provide a mote board construction adapted to cause all of the bolls, leaf, trash, dust and other foreign material to be thrown off by the centrifugal action of the saw cylinder doffing brush to be conducted away before the cotton lint is acted upon by the current of air which carries it through the gin conduit to the condenser, thereby preventing the air current from carrying the lighter impurities with the lint and consequently resulting in a cleaner cotton of a higher value.

With the foregoing and other objects in view, this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views, in which:

Figure 1 is a fragmentary section through a gin showing the improved mote board applied thereto.

Fig. 2 is a section on the line 2—2 of Fig. 1.

Fig. 3 is a fragmentary section showing a part of the mechanism for operating the mote board.

Fig. 4 is a section on the line 4—4 of Fig. 3.

Fig. 5 is an enlarged section through the upper end of the dirt passage wall, and

Fig. 6 is a detail perspective view of one of the mote board supporting members.

Referring more particularly to the drawings, 1 designates an ordinary saw cylinder

of a cotton gin, which saw cylinder is doffed by the rotary brush 2. And 3 indicates the conduit which conveys the clean cotton to the condenser.

A pair of supporting members 4 are pivotally connected to the sides 5 of the gin casing as shown at 6 and they include, the arm 7 and the substantially rectangular block portions 8 the upper edges of which are concavely curved as shown at 9 for forming a support for the mote board 10. The mote board 10 has its upper surface concavely cut to conform to the curvature of the doffing brush 2 and it is disposed in spaced relation to the doffing brush as clearly shown in Fig. 1 of the drawings, having its outermost ends overhanging the inner lower edge 11 of the conduit 3. The mote board 10 is attached to the members 4 in any suitable manner and its under surface is engaged by the crank portion 12 of a crank shaft 13. The crank shaft 13 is supported by suitable bearings 14 carried by the gin casing 5 and it has a hand lever 15 connected to its outer end, and positioned exteriorly of the gin casing. The hand lever 15 has a rib 15⁷ formed thereon which engages in any one of a series of notches 16 carried by a quadrant 17 for holding the hand lever in various adjusted positions. The pivotal movement of the hand lever 15 will rock the crank shaft 13 and consequently move the mote board 10 upon its pivot 6, for regulating the distance between the upper surface of the mote board and the rotary doffing brush 2.

A dust passage 20 is positioned within the gin casing 5 directly beneath the engaging portion of the brushes 21 of the doffing brush 2 and the periphery of the saw 1. The passage 20 extends downwardly, and is formed by an inner wall 22 and an outer wall 23. The walls 22 and 23 are connected to the blocks 4 by suitable bolts 24 entering the mote board 10 and if it is so desired spacing collars or sleeves 25 may be mounted upon the bolt 24 for holding the walls 22 and 23 in their proper spaced relation. The walls 22 and 23 have their upper edges bent inwardly, as shown at 26, so as to slightly constrict or reduce the mouth of the dust passage 20. The dust passage 20 is pro-

vided for carrying off the motes, dust, leaf trash and other impurities and foreign matter which would be thrown off by the centrifugal action of the rotary doffing brush 5 2, so as to prevent the air suction, which engages the cotton lint and carries it upwardly to the conduit 3, from carrying the lighter impurities upwardly to the condenser, with the ginned cotton. By connecting the walls 22 and 23 to the blocks 4, these walls and consequently the dust passage 20 will be adjusted, in accordance with the mote board 10, by the rocking action of the crank shaft 12. The upper edge of the 10 inner wall 22 terminates at the upper end of the mote board 10. By the arrangement of the mote board and walls 22 and 23 of the dirt passage 20, it will be seen that all of the motes, leaf trash, dust, and other impurities will be conducted away by the dirt 15 passage 20, prior to the action of the air current before the cotton, and thus a cleaner grade of cotton will be provided, in that the said air current will be prevented from carrying the lighter impurities upwardly 20 through the conduit with the cotton and by connecting the walls 22 and 23 to the pivotally hung members 4, these walls may be adjusted with the adjustment of the mote 25 boards so that the mouth of the dust passage will always be in the proper receiving position.

From the foregoing description taken in connection with the accompanying drawings 30 the advantages of construction and the method of operation of the improved mote boards for cotton gins will be readily apparent to those skilled in the art to which this invention appertains and, while in the 35 foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:

50 1. In a linting and delinting machine, movable fiber disintegrating and liberating means, a brushing member opposite the acting surface of said means and cooperating therewith, an adjustable pivoted conduit 55 wall adjacent said acting fiber liberating and disintegrating surface and extending away from the same, and spaced from one side of said brushing member, a substantially tubular educting passage mounted on said conduit wall at the end nearest the fiber disintegrating and liberating means, adjusting means on said educting passage regulating the inclination of the walls of said passage toward each other, an additional conduit 60 wall at the other side of said brushing mem-

ber and in spaced relation therewith and terminating near the end of the first mentioned conduit wall.

2. A linting and delinting machine as stated in claim 1 with the following additional features, the ends of both conduit walls partially overlapping each other and means to regulate the distance between said overlapping ends.

3. In a cotton gin structure, a saw cylinder, a rotary doffing brush, a pivotally supported mote board, means for adjusting the position of the mote board with respect to the doffing brush, and a pair of walls forming the dust passage connected to said mote board for adjustment therewith.

4. In a cotton gin structure, a saw cylinder, a rotary doffing brush, a pivotally supported mote board, a pair of walls connected to and extending downwardly from said mote board for forming a dust passage, said walls having their upper ends bent inwardly to form a constricted mouth for said passage, and means for adjusting the position of said mote board and dust passage with respect to said doffing brush.

5. In a cotton gin structure, a saw cylinder, a rotary doffing brush, a pivotally supported mote board, a pair of walls attached to and extending downwardly from said mote board for forming a dust passage, said walls having their upper ends bent inwardly to form a constricted mouth for said dust passage, and a crank shaft engaging said mote board for adjusting the position of the mote board and dust passage with respect to said rotary doffing brush.

6. A cotton gin structure including a saw cylinder, a rotary doffing brush for said saw cylinder, a conduit wall located beneath said doffing brush in spaced relation thereto, an inclined mote board arranged in spaced relation with said brush, an inner wall connected to said mote board and having its upper edge terminating at the upper edge of the mote board, and an outer wall connected to and held in spaced relation with said inner walls to form a dust passage.

7. A cotton gin structure including a saw cylinder, a rotary doffing brush for said saw cylinder, a conduit wall located beneath said doffing brush in spaced relation thereto, an inclined mote board arranged in spaced relation with said brush, an inner wall connected to said mote board and having its upper edge terminating at the upper edge of the mote board, and an outer wall connected to and held in spaced relation with said inner walls to form a dust passage, said inner and outer walls having their upper ends curved inwardly to form a constricted mouth for said passage.

8. A cotton gin structure including a saw cylinder, a rotary doffing brush, a conduit wall located beneath the doffing brush in

spaced relation thereto, an inclined mote board arranged in spaced relation with said brush and having its lower ends overlapping the inner edge of said conduit walls, an
5 inner dust passage wall connected to said mote board and having its upper edge terminating in the upper ends of the mote board, an outer wall connected to and held in spaced relation to said inner wall to form
10 a dust passage, means pivotally supporting

said mote board, and means for adjusting the position of said mote board with relation to said doffing brush.

In testimony whereof I affix my signature in presence of two witnesses.

JAMES L. WOOLDRIDGE.
